(57) **CLAIM**

The ornamental design for a dog bone shaped sauce tray, as shown and described.

DESCRIPTION

FIG. 1 is a front perspective view of the dog bone shaped sauce tray of the present invention.

FIG. 2 is a bottom perspective view of the dog bone shaped sauce tray of FIG. 1.

FIG. 3 a front view of the dog bone shaped sauce tray of FIG. 1.

FIG. 4 is a rear view of the dog bone shaped sauce tray of FIG. 1.

FIG. 5 is a right side view of the dog bone shaped sauce tray of FIG. 1.

FIG. 6 is a left side view of the dog bone shaped sauce tray of FIG. 1.

FIG. 7 is a top view of the dog bone shaped sauce tray of FIG. 1; and,

FIG. 8 is a bottom view of the dog bone shaped sauce tray of FIG. 1.
